UNITED STATES PATENT OFFICE.

CHARLES FOSTER FARNHAM, OF LORAIN, OHIO, ASSIGNOR TO AMERICAN STOVE COMPANY, OF ST. LOUIS, MISSOURI, A CORPORATION OF NEW JERSEY.

DESIGN FOR A DISPLAY-CARD.

59,955.

Specification for Design.

Patented Dec. 13, 1921.

Application filed December 8, 1920. Serial No. 429,295. Term of patent 14 years.

To all whom it may concern:

Be it known that I, CHARLES FOSTER FARNHAM, a citizen of the United States, residing at Lorain, in the county of Lorain and State of Ohio, have invented a new, original, and ornamental Design for a Display-Card, of which the following is a specification, reference being had herein to the accompanying drawings.

The accompanying drawing is a side view of my new design for display cards.

I claim:

The ornamental design for a display card, as shown.

In testimony whereof, I hereunto affix my signature.

CHARLES FOSTER FARNHAM.
